FROZEN CONFECTION

David L. Hendrick, Oakland, N.J., assignor to Consolidated Foods Corporation, Chicago, Ill., a corporation of Maryland

Filed Jan. 6, 1967, Ser. No. 5,335

Term of patent 14 years.

Int. Cl. D1—02

U.S. Cl. D1—22

The rear of the frozen confection opposite the front shown in FIGURE 1 is a mirror image thereof. The side of the frozen confection opposite FIGURE 3 is a mirror image thereof.

The essential features of the design reside in the portions shown in solid lines; a conventional stick handle being shown in broken lines in FIGS. 1, 3 and 4.

I claim:

The ornamental design for a frozen confection, substantially as shown and described.
